LOOSE LEAF BINDER PLATE

Fred A. Ravreby, 74 Booth St., Dedham, Mass.

Filed Aug. 5, 1963, Ser. No. 76,159

Term of patent 14 years

(Cl. D6—2)

FIG. 1 is a top perspective view of a loose leaf binder plate, showing my new design;

FIG. 2 is a front elevation thereof;

FIG. 3 is a rear elevation thereof;

FIG. 4 is an end elevation thereof as seen from the left of FIG. 3; and

FIG. 5 is a bottom plan view thereof.

I claim:

The ornamental design for a loose leaf binder plate, as shown.
